A. Wyckoff,

Chain Pump.

No 12,645.

Patented Apr. 3, 1855.

UNITED STATES PATENT OFFICE.

ARCALOUS WYCKOFF, OF COLUMBUS, OHIO.

CHAIN PUMP.

Specification of Letters Patent No. 12,645, dated April 3, 1855.

To all whom it may concern:

Be it known that I, ARCALOUS WYCKOFF, of Columbus, in the county of Franklin and State of Ohio, have invented a new and useful Improvement in Endless-Chain Pumps; and I do hereby declare that the following is a full, clear, and exact description of the same, reference being had to the accompanying drawing, forming part of this specification, in which—

Figure 1, is a vertical central section of an endless chain pump with my improvements. Fig. 2, is a horizontal section in the line α , α , in Fig. 1. Fig. 3, is a plan of one of the buckets or elevators. Fig. 4, is a plan of a valve somewhat different from the one shown in Fig. 2.

Similar letters of reference indicate corresponding parts in the several figures.

This invention relates to a method of rendering the pump capable of retaining its water above the level of the water in the well in case the motion of the chain is suddenly stopped.

The nature of the improvement consists in providing an elastic or other valve within the cylinder at a point just above the level of the water in the well, said valve being constructed and arranged in a manner to allow of the free passage of the elevators upward but to prevent all possibility of their return back with the water into the well in case the motion of the chain is suddenly stopped.

To enable others skilled in the art to make and use my invention I will proceed to describe its construction and operation.

A, A', A², represent the pump cylinder; B, the discharge of the same; C, the end-less chain; D, the chain wheel.

E, is the elastic and E', E', the metal disks of the elevators; F, the elastic valve; G, the seat of the valve and H, a ring for confining the valve in its place.

The cylinder A, A', has a bore of the same diameter from top to bottom excepting from the point b to c, where it is enlarged slightly owing to the bore of the ring H, which is inserted between these points, for confining the valve, being made of about one half inch greater diameter than the bore of said cylinder so as to allow for the expansion of the valve.

The valve F, may be divided in four parts and said parts hung on hinges as in Fig. 55 4, it may also be made elastic and provided with an annular hole c, and slitted radially as shown in Figs. 1 and 2 so that it shall be capable of yielding and opening sufficiently to allow of the passage of the elevators 60 through it. This valve owing to being arranged on the seat G, and the cylinder enlarged at d, b, is capable of opening upward, and as it thus opens is pressed against projection, d, and is prevented from opening to too great an extent, and as soon as the elevator escapes is caused in a measure by said projection d, to assume its seat again. The seat G, prevents the valve opening downward and consequently all possibility of the elevators returning back into the well with the water is prevented.

When an elevator comes in contact with this valve it causes the valve to expand and assume the position shown in dotted lines, 75 70 the elevator then escapes through the annular opening c, and the valve closes after it, and in case the motion of the chain is suddenly stopped the weight of the water causes the elevator to again descend until 80 it reaches the valve when its downward movement is arrested and all possibility of the water passing back into the well prevented.

By making the elevators with an elastic 85 disk, E, they are capable of passing more easily through the valve, and it is owing to their being made convex that the discharge of the water is facilitated.

Holes may be provided in the cylinder to 90 allow of the water running off slowly in case it is not useful to retain it in the cylinder.

What I claim as my invention and desire to secure by Letters Patent, is—

The application of an elastic or other suitable valve to an endless chain pump cylinder, said valve being arranged so as to be capable of only opening upward, substantially as and for the purpose herein set 100 forth.

ARCALOUS WYCKOFF.
